HIS ATTORNEY

UNITED STATES PATENT OFFICE.

JAMES J. BARRETT, OF WHITE PLAINS, NEW YORK, ASSIGNOR TO BARRETT BLUE BLAZE BURNER CO., INC., A CORPORATION OF NEW YORK.

OIL-BURNING APPARATUS.

Application filed January 9, 1924. Serial No. 685,165.

To all whom it may concern:

Be it known that I, JAMES J. BARRETT, residing at White Plains, county of Westchester, and State of New York, have invented certain new and useful Improvements in an Oil-Burning Apparatus, of which the following is a specification.

This invention relates to an improved oil burning apparatus, and one of the objects of the invention is to provide a new and improved oil burner.

Another object of the invention is to provide a liquid fuel burner, wherein more complete combustion of the liquid fuel is had than in burners of this character as hitherto constructed.

Another object of the invention is to provide a liquid fuel burner, which will not become clogged up by the carbonization of the constituents of the liquid fuel, and which may therefore be operated for long periods of time without care or attention, or the necessity of cleaning, to remove carbon deposits which in burners as hitherto constructed, interfere with their effective operation.

A further object of the invention is to provide an oil burner construction wherein the air utilized in the combustion of liquid fuel will be heated before being discharged into the burner.

Other objects and aims of the invention, more or less specific than those above referred to, will be in part obvious, and in part pointed out, in the course of the following description of the elements, combinations, arrangements of parts and applications of principles, constituting the invention; and the scope of protection contemplated will be indicated in the appended claims.

In the accompanying drawings, wherein I have illustrated a preferred form of embodiment of my invention:

Figure 1 is a vertical sectional view taken through the fire-box of a heating apparatus, also showing my improved burner in vertical section.

Figure 2 is a bottom plan view of a baffle plate, employed in connection with my invention.

Figure 3 is a vertical sectional view taken through a burner of a slightly modified construction.

Referring now to the drawings, wherein similar reference characters refer to similar parts throughout the views thereof, the reference numeral 1 designates the conventional form of furnace of a heating apparatus, provided with the usual flue 2.

Located within the chamber 3 of the fire-box, is my improved burner, illustrated at 4, the latter being preferably goblet shaped, as shown, supported by a vertical standard 5, mounted for vertical adjustment in a base 6, which rests upon the floor of the fire-box. Adjustment of the standard 5 may be accomplished as by means of the set screw 7. The burner 4 is preferably formed of a cup-shaped member, into which the liquid fuel 8 is discharged by means of a feed pipe 9, which leads from a float valve construction, 10, into which leads a conduit 11 from a source of oil supply 12. Any approved form of a float valve construction, illustrated at 10, may be employed, the object being to maintain a constant predetermined level of the liquid fuel 8 in the burner 4.

Extending laterally into the burner 4 is a conduit 13, which conduit terminates in a downwardly extending funnel-shaped outlet end or nozzle 14, located centrally of the interior of the burner. Inasmuch as the conduit 13 within the burner is directly above the burning liquid fuel, the air discharged thereto will be preheated before it passes through the outlet end or nozzle 14. The outlet end or nozzle 14 discharges the preheated air downwardly into the central portion of the flame, the construction being such that the preheated air is forced against the entire surface of the burning liquid fuel. Surrounding the outlet or nozzle 14 is a circular plate or baffle 15. The discharge opening of the nozzle 14 is located slightly above the normal level of the liquid fuel.

The burner 4 is surmounted by a baffle plate 16, having the legs 17, which rest upon a circular flange 18, formed exteriorly of the burner. This baffle plate 16 is located above the upper open end of the burner 4, providing the space 19, through which the flame from the burner passes into the fire-box. The air conduit 13 is connected by means of the conduit 20, with a source of air supply, such for instance as

the blower 21. Located between the conduits 20 and 13 is a valve 22, and located in the fuel conduit 9 is a valve 23.

The valves 22 and 23 are provided with 5 the arms 24 and 25 respectively, having their outer ends adjustably mounted in the slots 26 and 27 of a rod 28, adjustably mounted as at 29 in a slot formed in an operating handle 30. It will be seen that 10 by means of this last described construction the valves 22 and 23 may be operated in synchronism, and the operative relation of said valves may be changed by adjusting their operating handles in the slots 26 and 15 27 of the rod 28.

Mounted upon the standard 5 is a cup 31 adapted to hold a small quantity of liquid fuel, which liquid fuel may be discharged into said cup through a nozzle 32, 20 provided upon a branch conduit 33, leading from the fuel conduit 9, which branch conduit is controlled by means of the valve 34.

Referring now to the embodiment of my 25 invention shown in Figure 3 of the drawings, the burner 4, which is formed similarly to that already described, has leading through the bottom wall thereof an air conduit 35, the upper end 36 of which terminates slightly above the level of the liquid fuel in the burner. The baffle plate 16 has a downwardly extending stem 37, the latter carrying a baffle plate 38, against which the air which is discharged through 30 35 the tube 35 is projected.

Having thus described my invention, the operation thereof, which should be largely understood, is substantially as follows:

It will be understood that Figure 1 of 40 the drawings shows schematically the burner and its associated parts comprising the system, ready for operation. The liquid fuel within the burner may be initially ignited by thrusting a torch through the aperture 19 between the baffle 16 and the upper end of the burner into the body of liquid fuel contained therein.

Prior to this operation, the liquid fuel contained in the cup 31 has been ignited 50 in a similar manner, the operation of this fuel preheating the fuel within the burner, rendering it easier to ignite. When the fuel in the burner has been ignited, the valves 22 and 23 are opened, whereby when 55 the blower 21 is set into operation, air is discharged downwardly through the nozzle 14, upon the burning fuel within the burner. The flames pass upwardly through the open upper end of the burner, outwardly, into 60 the fire-box, through the aperture 19, beneath the baffle plate 16.

Referring again to Figure 1 of the drawings, I have shown a conduit 39 connected with the conduit 20. The conduit 39 will 65 preferably lead from a source of steam sup-

ply, not shown. It is within the scope of the present invention to discharge steam under pressure into the burner through the nozzle 14, when once the operation has been started by the use of air.

The operation of the embodiment of my invention shown in Figure 3 is similar to that above described. In this construction, however, the air entering the burner through the conduit 35 impinges against 75 the baffle 38, the flames being discharged through the aperture 19, between the upper end of the burner and the baffle 16, as in the first described embodiment of my invention.

It will accordingly be seen that I have provided a construction well adapted to attain, among others, all the aims and objects above pointed out. It will be noted that the air entering the burner will be preheated before its discharge from the nozzle 14 against the surface of the flaming liquid fuel.

It will also be noted that the burner can be cleaned automatically by closing the 90 valve 23, thereby shutting off the supply of liquid fuel to the burner, whereby when the volume of liquid fuel gradually decreases in the burner, all carbon deposits will be removed.

It will also be noted that the relative adjustment of the valves 22 and 23 provides for the discharge into the burner of the desired proportions of air or steam and the liquid fuel.

As many changes could be made in this construction without departing from the scope of the following claims, it is intended that all matter contained in the above description, or shown in the accompanying 105 drawing, shall be interpreted as illustrative only and not in a limiting sense.

Having thus described my invention what I claim as new and desire to secure by Letters Patent is:

1. A burner of the class described, comprising in combination, a receptacle adapted to hold a quantity of liquid fuel, means located beneath said receptacle for maintaining a quantity of liquid fuel, which when ignited is employed to heat the body of liquid fuel within said receptacle, a baffle plate surmounting said receptacle, and spaced from the upper open end thereof, means for discharging air, steam or other fluid against the surface of the liquid fuel within said receptacle, said means for discharging said fluid, being partially located within said burner, so that the fluid will be preheated before it is discharged into the burner, and means for simultaneously controlling the flow of liquid fuel and fluid into said burner.

2. In an oil burner of the class described the combination of a receptacle having an 130

- opening upwardly therethrough, means for feeding a liquid fuel into the receptacle to a predetermined level, a baffle supported by the receptacle at a location above the baffle 5 with the baffle depending within the receptacle in spaced relation at its outer edges from the inner wall of the receptacle and so that a transversely unobstructed space is provided between the baffle and the liquid 10 level, and means for discharging a blast of air into the receptacle into the space between the baffle and the liquid level in the receptacle whereby the blast of air and the vaporized oil therewith must travel between 15 the outer edge of the baffle and the inner surface of the receptacle upwardly towards the opening in said receptacle.
3. In a fuel burner the combination of a receptacle, a baffle supported above the receptacle in a spaced relation thereto, means for feeding a liquid fuel into the receptacle to a certain level, a second baffle supported within the receptacle, and means for feeding a blast of air into the receptacle between 25 the second baffle and the liquid level.
4. In an oil burner the combination of a receptacle having an opening in the upper end thereof, means for supplying a liquid fuel to the receptacle to rise to a predetermined level, a baffle supported by the receptacle providing a convex baffle surface located within the receptacle in spaced fac-
- ing relation above the liquid level, and means for discharging air into the receptacle at a point directly between the liquid level 35 and said baffle.
5. In an oil burner of the class described the combination of a receptacle having an opening upwardly therein, means for feeding a liquid fuel into the receptacle to a predetermined level, a baffle, means supporting the baffle within the receptacle from a point above the liquid level and in spaced transversely unobstructed, relation with the liquid level, and means for feeding a blast 40 of air into the unobstructed space between 45 the baffle and the liquid level in a direction normal to the liquid level.
6. In a fuel burner the combination of a receptacle, a baffle supported by the receptacle providing a baffle surface disposed within the receptacle, means for feeding a liquid fuel into the receptacle to a predetermined level located in spaced relation 50 below said baffle surface, means for feeding 55 a blast of air into the receptacle between the said baffle surface and the liquid level, said receptacle at its upper end being open, and deflecting means facing said opening to laterally direct the flames and heated medium 60 from said receptacle.

In testimony whereof, I affix my signature.

JAMES J. BARRETT.
